UNITED STATES PATENT OFFICE.

WALTER E. PREBLE, OF NEW YORK, N. Y.

DESIGN FOR A TAG HOLDER OR FASTENER.

SPECIFICATION forming part of Design No. 15,622, dated December 16, 1884.

Application filed August 25, 1884. Term of patent 3 years.

To all whom it may concern.

Be it known that I, WALTER E. PREBLE, of the city, county, and State of New York, have invented a new and original Design for a Tag Holder or Fastener, of which the following is a full, clear, and exact description.

My design for a tag holder or fastener embraces both an alphabetical and numerical figure, the same consisting in the representation of the letter **X** and figure **8**, combined as hereinafter described, and shown in the annexed drawing.

Reference is to be had to the accompanying drawing, forming a part of this specification, which represents a perspective view of a tag holder or fastener embodying my design.

A designates the upper looped portion, and B the lower looped portion, of the tag holder or fastener, and C the crossing portion of said two parts. These several parts present a general configuration which resembles the figure **8**, and where the two loops or looped portions A, B cross each other a well-defined and approximately straight-limbed letter **X**.
25 The upper looped portion, A, is here rep-

resented as both shorter and narrower than the lower looped portion, B, and with its sides B B parallel with each other and straight, or nearly so, and its ends c c of tapering form, but projecting inward at right angles, or nearly so, in reverse directions from the sides b b, thus forming a nearly rectangular-shaped loop, while the lower looped portion, B, is of curvilinear shape, presenting two slightly-convex sides, d d, and a lower sharp or quick convex end, e. The limbs f f of the crossing portion C are straight.

I claim—

The within-described design for a tag holder or fastener, which consists in the representation of the figure **8**, having a rectangularly-shaped upper looped portion, A, and curvilinearly-shaped lower looped portion, B, and intermediate straight-limbed crossing portion, C, representing the letter **X**, as shown. 40 45

W. E. PREBLE.
